UNITED STATES PATENT OFFICE.

ORRIN L. MERRITT AND WILLIAM P. JONES, OF STOCKTON, CALIFORNIA.

STEAM-CONSERVER FOR CANNERY COOKERS AND EXHAUSTS.

1,344,809.

Specification of Letters Patent. Patented June 29, 1920.

Application filed March 7, 1919. Serial No. 281,153.

To all whom it may concern:

Be it known that we, ORRIN L. MERRITT and WILLIAM P. JONES, both citizens of the United States, residing at Stockton, in the 5 county of San Joaquin, State of California, have invented certain new and useful Improvements in Steam-Conservers for Cannery Cookers and Exhausts; and we do declare the following to be a full, clear, and 10 exact description of the same, reference being had to the accompanying drawings, and to the characters of reference marked thereon, which form a part of this application.

15 This invention relates to improvements in steam conservers for cannery cookers and exhausts.

In the present state of the canning art, the canned product is subjected to two steam 20 treatments one to heat the product sufficiently to discharge or exhaust the air therefrom prior to the cover being put onto the can or sealed, and the other to cook the product after the covers have been sealed on.

25 Some products need to be cooked under pressure. With present methods it is necessary to place the products in a closed retort. Our device is intended and adapted to be used with such cooking retorts to save the 30 steam therein and prevent its escape.

The prime object of our invention therefore is to do away with this waste of steam and the conditions accompanying such waste, and to introduce the cans into and 35 out of the cooker in a manner to prevent the escape of steam therefrom by the interposition of our steam conserver in the port or entrance to the exhaust or cooker.

Another object is to provide a simple and 40 inexpensive device, and yet one which will be extremely efficient for the purpose for which it is designed.

These objects we accomplish by means of such structure and relative arrangement of 45 parts as will fully appear by a perusal of the following specification and claims.

On the drawings, similar characters of reference indicate corresponding parts in the several views.

50 Figure 1 is a top plan view of our improved steam conserver, showing the same attached to a cooker, and with one half of the top removed to show certain details thereunder.

Fig. 2 is a longitudinal cross section of 55 the same.

Fig. 3 is a top section taken on a line 3—3 of Fig. 2.

Fig. 4 is an end elevation of the conserver partly broken out, looking at the end adapted to be attached to the cooker.

Referring now more particularly to the numerals of reference on the drawings, the numeral 1 indicates the base plate of the device, which is adapted to be supported 65 from the floor by adjustable standards 2.

Turnably mounted in the base is a vertical shaft 3 on which is keyed a circular smooth surfaced plate 4, to which and above the same is secured a circular can conveyer 5, 70 the latter being provided with a plurality of suitably sized niches or recesses 6 for the reception of cans therein.

The members 4 and 5 are surrounded by a flanged casing 7 bolted to the base plate 75 1 and extending part way around the periphery of the can receiving members, and by a flanged member 8 of bronze or some similar metal, which abuts against the ends of the casing 7 and follows the periphery of 80 the members 4 and 5 for the distance between the aforesaid ends of the casing.

The casing is provided with a rectangular orifice 9 therein, of a size suitable to permit free passage of a can therethrough while the 85 member 8 is provided with an orifice 10 of similar size to the orifice 9. The flanges 11 of this member 8 are drilled to adapt the same to be bolted over the entrance flange 12 of the cooker 13, which cooker has a rotating receiving disk 13^a suitably positioned 90 in the entrance as is the common custom.

A cover 14 is bolted to the casing 7 and extends over the member 5 all around the same, but is spaced therefrom. This cover and the member 7 are provided with alined lugs 15 which have adjustment bolts 16 therethrough, there being similar lugs 17 and bolts 18 on the under side of the member 8 and the base plate 1 by means of which 100 the member 8 is connected to the cover and base and may be adjusted to a nicety with regard to the periphery of the member 5.

The outer periphery of the member 5 and the inner periphery of the member 8 105 are machined and ground to as smooth surfaces as possible, in order that a steam tight joint will be formed therebetween.

for a purpose as will appear. It is not necessary, however, that the member 5 should have close bearing contact with the casing 7.

- 5 Positioned in front of the orifice 9 in the casing 7 and turnably mounted in the base 1 is a shaft 19 on which is secured a disk 20 whose upper face is finished smooth and is on a level with the level of the plate 4.
- 10 Secured to the shaft 19 above the disk 20 is a spider 21, whose arms are adapted to receive the cans delivered onto the disk 20 in spaced sequence from the filler by means of a conveyer or disk suitably positioned relative thereto as is common in the art.

A guide bar 23 projects from the side of the casing 7 to insure the cans being forced through the orifice 9 into the recesses 6 in the member 5.

- 20 This spider feeding mechanism is a common form of device used in canneries for this purpose, and we do not make any claims of novelty therefor.

It is of course understood that the member 5 is arranged to constantly rotate, and the spider 21 likewise but in the opposite direction, the ratio of speed and the correct positioning of the recesses 6 relative to the arms of the spider 21 being designed so that such positioning will occur continually during the rotation of the members. This suitable rotation is accomplished by the following means:—

On the shaft 19 below the base 1 is a bevel gear 24 meshing with a similar gear 25 on a drive shaft 26, supported in bearings 27 depending from the base 1, which shaft may be driven from any suitable source of power by means of a gear or sprocket 28 on said shaft.

On the shaft 26 is another bevel gear 29 meshing with a gear 30 on the shaft 3, the size of the gear 30 relative to the gear 24 being reversely proportionate to the number 45 of recesses 6 relative to the arms of the spider 21, in this case 5 to 3. In other words, the gears are such that the member 5 will make 1 revolution to every $1\frac{2}{3}$ revolution of the spider.

50 Mounted in the member 5 and to one side of each recess 6 therein are rods 31 projecting up through the member 5 into the space between the same and the cover 14 and each having on that end a horizontal 55 arm 32 adapted to bear against a pin 33 depending from the stationary cover 14.

On the lower portion of each rod 31 is a curved bar 34, normally resting against the surface of the recess.

60 The pin 33 is so positioned in the cover that with the rotation of the member 5, when each recess 6 comes into register with the exit passageway or orifice 10, the arm 32 will be forced to turn and the bar 34 65 will be moved outwardly and will cause the

can held in the recess 6 to be forced out therefrom and into the cooker 13, where it is taken by any of the various forms of conveyers used in the art.

As soon as the arm 32 passes out of range 70 of the pin, which will be when the can has been completely forced out of the recess 6, the rod 31 will snap back to its normal position, owing to suitable spring tension means 35 connected thereto. 75

In operation, the cans are first delivered into each successive recess 6 by the spider 21, the member 5 turning in a clockwise direction, as indicated by the arrow. When each recess 6 is in alinement with the exit 80 or discharge orifice 10, the can therein is forced into the cooker 13, as previously explained. This recess then becomes full of steam, and continues so until with the further rotation of the member 5, the orifice 85 is completely inclosed by the member 8. At this point, a pipe 36 is interposed in the side of the member 8 which leads to one end of a cylinder 37 in which travels a piston 37^a actuated by a rod 38 which is 90 operatively connected with an inclosed cam 39 turned by suitably timed gearing 40 from the drive shaft 26.

This piston is on the outward or suction stroke for the entire peripheral length of 95 each recess 6 while the same is crossing the path of the pipe 36. As soon as said recess has passed the pipe 36, the latter is closed by the outside face of the member 5. During this period of rotation the backward 100 stroke of the piston 37^a takes place. As the steam cannot escape through the pipe 36, a check valve 41, which opens outwardly, is interposed at any suitable point therein, and the steam is forced thence into a pipe 105 42, which may lead where desired to again utilize the steam.

It will be noted that the peripheral width of the recesses being considerably greater than that of the circular portion of the 110 member 5, the outward movement of the piston must take place for a greater proportionate period in the rotation of the drive shaft 26 than the return movement. Hence, we have shown a cam movement which may 115 easily be designed to give the required proportionate times of travel.

Although of course a small amount of steam will remain in the pockets or recesses 6, the greater majority will be drawn out by 120 the means just described.

From the foregoing description it will be readily seen that we have produced such a device as substantially fulfills the object of the invention as set forth herein.

125 While this specification sets forth in detail the present and preferred construction of the device, still in practice such deviations from such detail may be resorted to as do not form a departure from the spirit 130

of the invention, as defined by the appended claims.

Having thus described our invention, what we claim as new and useful and desire to secure by Letters Patent is:—

- 5 1. The combination with a cannery cooker of a cylindrical casing adapted to be secured over the entrance to the cooker and having communication therewith, a rotatable member in the casing provided with peripheral recesses in spaced sequence and adapted to receive cans therein, a pivotally mounted rod in the edge of each recess, a curved arm on the rod normally spring-pressed against the face of the recess positioned therein and adapted to partly encircle a can, and means to turn the rod and cause the arm to sweep across the recess when such recess registers with the entrance to the cooker.
- 10 2. The combination with a cannery cooker of a cylindrical casing adapted to be secured over the entrance to the cooker and having communication therewith, a rotatable member in the casing provided with peripheral recesses in spaced sequence and adapted to receive cans therein, a pivotally mounted rod in the edge of each recess, a curved arm on the rod normally spring-pressed against the face of the recess positioned therein and adapted to partly encircle a can, a short spring-held arm on the rod above the recess, and a pin in the casing adapted to abut against the short arm to turn the rod and cause the curved arm to sweep across the recess when the latter registers with the entrance to the cooker.
- 15 3. The combination with a cannery cooker of a cylindrical casing adapted to be secured over the entrance to the cooker and having communication therewith, a rotatable member in the casing provided with peripheral
- 20 recesses in spaced sequence and adapted to receive cans therein, the rotatable member having steam tight connection with the casing, and the latter being provided with an inlet opposite its connection with the cooker, and a suction pump communicating with the casing at a point between the inlet thereof and its opening into the cooker, the suction stroke of the pump coördinating with the rotation of the recessed member to draw steam from each recess when the same has passed the entrance to the cooker a predetermined distance.
- 25 4. A steam conserver for cannery cookers comprising in combination with a cooker having an entrance port in the side thereof, a horizontal base plate supported from the ground and positioned adjacent the entrance, a semicircular casing on the base plate provided with an orifice in the side thereof adapted to pass cans therethrough, a circular rotatable member in the casing provided with peripheral recesses adapted to receive cans therein, a semicircular flanged member adapted to be secured to the cooker over the entrance thereof, the flanged member being provided with an orifice for the passage of cans therethrough and forming a steam tight connection with the periphery of the rotatable member, and adjustable means whereby the said member may be both attached to the base plate and casing and adjusted relative to the rotatable member.
- 30 5. In testimony whereof we affix our signatures in presence of two witnesses.
